[57] CLAIM

The ornamental design for a cover for a plumbing fixture or the like, as shown and described.

DESCRIPTION

FIG. 1 is a top perspective view of a cover for a plumbing fixture or the like showing my new design;

FIG. 2 is a top plan view thereof;

FIG. 3 is a front elevational view thereof;

FIG. 4 is a right side elevational view thereof, the left side being the mirror image of the right side;

FIG. 5 is a bottom plan view thereof;

FIG. 6 is a rear elevational view thereof;

FIG. 7 is a cross sectional view taken along line 7—7 of FIG. 2; and

FIG. 8 is a cross sectional view taken along line 8—8 of FIG. 2;

The broken line representation of a fitting hole in FIGS. 1, 2 and 5 are for illustration only.

FIG. 1

FIG. 2

FIG. 3

FIG. 4

FIG. 5

FIG. 6

FIG. 7

FIG. 8
